UNITED STATES PATENT OFFICE.

WILLIAM H. HILL, OF MANATI, PORTO RICO.

KEROSENE VAPORIZER.

1,424,142.

Specification of Letters Patent. Patented July 25, 1922.

Application filed August 28, 1918. Serial No. 251,765.

To all whom it may concern:

Be it known that I, WILLIAM H. HILL, a citizen of the United States, residing at Manati, Porto Rico, have invented certain new and useful Improvements in Kerosene Vaporizers, of which the following is a clear, full, and exact description.

This invention relates to apparatus for volatilizing or vaporizing liquid fuels, and particularly to apparatus in which the liquid fuel is transformed into its gaseous or vaporized state without first being atomized.

An object of the invention is to provide a liquid fuel volatilizing apparatus in which the heavier liquid fuels, such as kerosene, may be completely or substantially completely volatilized without injury to the combustible properties of any of the constituents of the fuel.

Another object of the invention is to provide apparatus for volatilizing liquid fuels, in which the volatilizing means acts directly upon the fuel, that will operate to vaporize only enough fuel to meet the demands upon the apparatus, as, for example, when operating in conjunction with an internal combustion motor.

The invention aims also to provide means for volatilizing a liquid fuel, in which each of the constituents of the fuel will be acted upon directly by the volatilizing means and yet will be volatilized at a temperature which will secure complete or substantially complete volatilization without excessive heat.

An important feature of the invention is the arrangement, in combination with a differentially heated surface for effecting the volatilization of the constituents of the fuel at heats appropriate to the respective constituents of means for directing the fuel to be volatilized over said surface in a film and in such manner that the selective volatilization is effected by the appropriately heated parts of the surface.

Another important feature of the invention is the provision of means for at once conducting away from the volatilizing means the different constituents of the fuel as they are volatilized, and of means whereby the action of the apparatus is proportioned to the demand made upon it.

Another important feature is the provision of means for maintaining the temper-

ature of the volatilized fuel on its way to the engine.

Other objects and important features of the invention will appear from the following description and claims when considered in connection with the accompanying drawings, in which

Fig. 1 is a sectional view taken approximately centrally of my apparatus;

Fig. 2 is a section on the line 2—2, Fig. 1; 65

Fig. 3 is a sectional detail of the lower central portion of Fig. 1;

Fig. 4 is an elevation;

Fig. 5 is a sectional view of the mixing chamber shown at 34, Fig. 4; 70

Fig. 6 is a side elevation of said chamber as viewed from the right, Fig. 4;

Fig. 7 is a section on the line 7—7, Fig. 1, and

Fig. 8 is an end view, looking from the left in Fig. 1, of the heating chamber through which the exhaust passes.

As hereinabove suggested, the liquid fuel volatilizing means of the present invention is intended to operate directly upon the fuel without the intervention of means for atomizing the fuel or mixing it with air. To this end the illustrated device comprises a cylindrical chamber 2, bounded by a wall 4, which constitutes the volatilizing means proper, this wall being arranged to be differentially heated so that different parts of the wall are heated to different temperatures. The chamber also has a bottom 5 provided with an internally threaded extension or hollow boss 7. 90

The means for heating the wall 4 of the chamber 2 in the illustrated construction comprises a casing 10 having open ends 12 and 14, constituting, respectively, intake and exit openings for the motor exhaust gases or other suitable heating fluid. The casing 10 is shaped between its ends 12 and 14 to receive the lower flanged part of the volatilizing means, this part of the wall 4 of the volatilizing means being provided with relatively wide heat-collecting flanges 16, the upper one of which, shown at 18, is provided with a shoulder 20 bearing against the upper face of the casing 10. The heat collecting flanges 16 offer considerable resistance to the passage of the gases through that portion of the exhaust passageway occupied by them and it may be desirable at times to permit a freer passageway for the exhaust 110

gases. To this end the casing 10 has a lower projecting portion 11 forming with the partition 13, a chamber for the free passage of the gases when the pressure thereof is such as to open a spring controlled flop-valve 15 which normally closes the entrance to the free passageway. This valve is connected to a rock shaft 17 extending through the casing 10 and having outside of its casing an arm 19 connected to a spring 21, which holds the valve 15 yieldingly in closed position. The lower end of the chamber 2 may be seated in the partition 13 and secured to the casing 10 by a nut engaging the discharge pipe 8 which is threaded into the boss 7, said nut engaging the projecting portion 11 of the casing 10.

Above the flange 18 and outside the casing 10, the wall 4 of the volatilizing chamber 2 is provided with heat radiating flanges 24, which are preferably somewhat narrower than the heat collecting flanges 16.

The heat collected by the flanges 16, and directly collected by the wall 4 within the casing 10, is conducted to some extent up through the wall 4 and outside said casing. A part of this heat will be radiated by the lower flanges 24, thus reducing the temperature of the wall just outside the casing 10 below that inside said casing, and the further radiating action of the flanges 24 above the lower flanges 24 will cause a still further reduction of the amount of heat conducted up the wall, thus producing a decided differential in the temperature of the wall 4 at different points, the upper end of the wall being the least heated.

The object of thus differentially heating the wall 4 is to provide for volatilizing the different constituents of the liquid fuel, for example kerosene, at their appropriate heats of volatilization without over-heating, and the purpose of the particular relative arrangement of the differently heated parts of the surface in the illustrated device is to provide for passing the fuel to be volatilized first over the least heated parts of the surface, in order first to volatilize the more volatile constituents of the fuel before the less volatile parts are directed over the more heated parts of the surface. In the illustrated construction, the fuel to be volatilized is introduced into the upper end of the chamber 2 and is caused to flow down over the surface of the wall 4 in a relatively thin film, means being provided for directing the fuel to be volatilized substantially over the whole inner surface of the wall 4.

The illustrated means for introducing the liquid fuel to be volatilized into the volatilizing means, and for directing it over the heat imparting surface of the wall 4, comprises a chambered part 26 threaded upon the upper part of the wall 4, the wall 4 having an exteriorly beveled or frusto-conical part 30

projecting into the chamber 28 within the member 26, the inner wall of the chamber 28 about the beveled upper end 30 of the wall 4 being cylindrical. An annular groove 35 is thus provided about the upper end of the wall 4, this groove being adapted to carry the liquid fuel about the upper end of the wall 4, and to constitute a spillway from which the liquid fuel will be fed to the inner surface of the wall 4 to meet the demands upon the volatilizing means. The liquid fuel to be volatilized is preferably fed to the wall of the chamber 2 in a thin film by means of the bell 32, which has a fluted lower edge fitting within the part 30 of the chamber 2. The upper contracted portion of the bell 32 is provided with an opening through which the volatilized fuel passes to the mixer 34, and thence to the manifold 36. Under suction of the engine the liquid fuel is drawn from container 38 through the conduit 40, and is delivered to the chamber 28 at the groove 35, the overflow running between the fluted end of the bell 32 and thus down the walls of the cylindrical chamber 2, in a thin film. The container 38 is connected by a supply pipe 42 with some source of fuel supply from which the fuel may flow by gravity to the container, the amount therein being regulated by a float 44, operating to open and close a valve in the pipe 42 as the position of the float varies.

In the position of the parts shown in Fig. 1, fuel will be fed to the chamber 2 and volatilized therein, the more easily volatilized portions first, and these after volatilization will tend to flow toward the top of the chamber 2 and into the bell 32, from whence they are conducted through a valve 48, to the mixer 34 by way of the conveyor pipe 50, said pipe being preferably provided with openings 52 to permit a ready mixing of the volatilized fuel with the air, which is directly admitted to the mixer 34 through the intake 54. A valve 56 controlled by a lever 58 regulates the amount of mixture admitted. From the mixer 34 the gases pass to the manifold 36.

The volatilized fuel is drawn from the bell at a high temperature, and in order to maintain this temperature while the volatilized fuel is passing to the mixer, the conveyor pipe 50 after passing through a chamber 60 containing a regulating device 62, enters a jacket 64, which forms a portion of a by-pass from a part of the exhaust 66 to that part including the casing 10. A connecting pipe 68, in which may be included a valve 70 to regulate the amount of the exhaust gases going through the by-pass, connects the part 66 to the jacket 64. Also connected to the lower portion of the jacket, is a pipe 72 joined to the pipe 74 by a union 76.

When the demand upon the volatilizing apparatus is relatively low, as, for example,

when the engine is idling, it is preferable that the heat imparted to the volatilizing means shall be localized, and to this end means is preferably provided for automatically locally varying the heat imparted to the wall 4, in accordance with the variation in the demand made upon the volatilizing means. The illustrated means comprises a valve or vane 78 carried upon a rock-shaft 80 in the casing 10 and arranged to swing across the inlet opening 12 and across the path of flow of the exhaust gases through the casing 10. Outside the casing, the shaft 80 is provided with an arm 82, to which is connected a spring 84 attached at its other end to the casing 10, the spring 84 tending to move the valve or vane 78 in the direction to close the opening 12.

From an inspection of Fig. 1 of the drawings, it will be seen that the valve or vane 78 will be swung more or less toward a horizontal position, in accordance with the pressure or speed of flow of the exhaust through the casing 10, and that the exhaust will therefore be directed over a greater or less number of the heat gathering flames 16, in accordance with the pressure exerted upon the vane 78. In order further to insure such direction of the exhaust, extensions 86 of the flanges 16 are preferably cast integral with the casing 10 and so shaped that they substantially meet the path of swing of the lower end of the vane 112, thus shutting off the upper flanges 16 from the exhaust gases.

When supplying an internal combustion motor, said motor may be started by the temporary use of a more easily volatilized fuel than that designed to be ordinarily used, such, for instance, as gasoline. While an ordinary electric primer may be used, I prefer to use the gas from a gasoline carburetor which may be temporarily connected to the intake 54 of the mixer. During this operation the valve 48 is closed. The exhaust gases from the motor will pass through a portion 66 of the exhaust which is connected to the portion 10 thereof, some of the gases going through the by-pass and heating up the jacket 64. When the chamber 2 has been sufficiently heated by the gases passing over the heat collecting flanges 16, the valve 48 is opened and liquid fuel is sucked into the chamber 2 where it is volatilized as previously described. Connection to the gasoline line carburetor may then be shut off.

Any excess or heavy fuel collecting in the bottom of the chamber 2 will flow through the opening 88, Fig. 3, in the boss 8, and out through the holes 90 in chambered nut 92. A gravity valve, in the shape of a ball 94 closes the lower end of the opening 88 under the suction of the engine to prevent air from being admitted through the holes 90 to the chamber 2.

While in the drawings the mixer 34 is

shown near the gasifying chamber 2, nevertheless in practice, these parts may be separated by considerable distance, and for this purpose, a part of the connection between the pipe 72 and the mixer 34 may be made flexible. Thus the conveyor pipe 50 and jacket 64 may be made of flexible tubing, one within the other throughout a portion of their length.

It may be mentioned that the adjustment of the apparatus is preferably such that the supply of volatilized fuel is delivered at the mixer 34 at substantially atmospheric pressure and that when this pressure is changed by the suction of the engine, the liquid fuel 80 is drawn into the gasifier where it is volatilized, thereby reestablishing the pressure balance, thereby stopping the flow of liquid to the gasifier.

This application is a continuation in part of my prior applications, Serial No. 233,233, filed May 8, 1918, and Serial No. 243,172, filed July 3, 1918.

Claims to the broad idea of differentially heating a vaporizing surface and causing the liquid fuel to be vaporized to be directed onto this surface and to pass over it in the direction of increasing heat have been transferred from this application to my co-pending application #435,779, filed Jan. 8, 1921, fuel vaporizer, which is in part a continuation of the present application. Claims to the subject matter common to this application and to said co-pending application have been made in said co-pending application.

Having thus described my invention, what I desire to secure by Letters Patent is:—

1. In an apparatus of the character described, the combination with the exhaust chamber of an internal combustion motor, of means arranged in the path of the gases through said chamber for absorbing a portion of the heat of said gases, said heat absorbing means offering resistance to the passage of the gases, and a valve-controlled by-pass arranged to relieve excessive back pressure, said valve being yieldingly held in closed condition and arranged to open under a predetermined pressure. 110

2. In an apparatus of the character described, the combination of a chamber into which the liquid fuel to be volatilized is introduced, means for distributing the fuel evenly over the walls of the chamber comprising a member fluted at its edges and fitting into said chamber and means for supplying fuel to said member. 120

3. In an apparatus of the character described, the combination of a chamber into which the liquid fuel to be volatilized is introduced, a bell having fluted edges, and an opening at its contracted portion, and means for supplying fuel to said bell, the fluted edges thereof engaging within the 125

walls of said chamber and serving to equally distribute the fuel over the walls thereof, and the opening in the bell serving to permit the passage of the volatilized fuel.

5 4. In apparatus of the class described for use with internal combustion motors, in combination, means for volatilizing a liquid fuel, comprising a heated surface over which the fuel to be volatilized is directed, and 10 means for varying the heat imparted to said surface in accordance with the demand made upon said volatilizing means.

5 5. In apparatus of the class described for use with internal combustion motors, in combination, means for volatilizing a liquid fuel, comprising a heated surface over which the fuel to be volatilized is directed, and 15 pressure controlled means for varying the heat imparted to said surface in accordance with the demand made upon said volatilizing means.

5 6. In apparatus of the class described for use with internal combustion motors, in combination, means for volatilizing a liquid 20 fuel, comprising a heated surface over which the fuel to be volatilized is directed, means 25 for heating said surface from a motor exhaust, comprising heat collecting flanges, and means for directing said exhaust over 30 a greater or lesser number of said flanges in accordance with the demands made upon said volatilizing means.

5 7. In apparatus of the class described, in combination, means for volatilizing a liquid 35 fuel, comprising a gas receiving chamber having a heated wall over which the fuel to be volatilized gravitates, means for heating said wall arranged to direct a heating medium over the lower part of the opposite 40 side of said wall, and means for varying the relative proportion of the parts of said

wall directly exposed to the heating medium and those heated by conduction from the directly heated parts.

8. In apparatus of the class described for 45 use with internal combustion motors, in combination, volatilizing means comprising a gas receiving chamber having a heated wall over which the fuel to be volatilized is directed, heat gathering and heat radiating 50 flanges upon the opposite side of said wall, and means for varying the relative numbers of said flanges employed for the two purposes in accordance with the demand made upon said volatilizing means. 55

9. Liquid fuel vaporizing means comprising, in combination, a chamber presenting a fuel heating surface over which the fuel to be vaporized is passed, means external to said chamber for heating said surface, and 60 heat radiating means for producing a differential heating of said surface.

10. Liquid fuel vaporizing means comprising, in combination, a chamber presenting a fuel heating surface over which the fuel 65 to be vaporized is passed, means for heating said surface, and means for effecting a differential heating of said surface comprising heat collecting means adjacent to portions of said surface, and heat radiating means 70 adjacent to other portions of said surface.

11. In apparatus of the class described, the combination with a vertically arranged cylindrical chamber having an inlet near its upper end and an axially arranged outlet, of means for heating the lower end of 75 said chamber, and radiating means for radiating away a part of the heat conducted to the upper part of said chamber.

Signed at San Juan this 12 day of August 1918.

WILLIAM H. HILL.
